DESIGN FOR A SIPHON BOTTLE

Archie Towart, Jr., West Caldwell, N. J., assignor to Walter Kidde Sales Company, Bloomfield,
N. J., a corporation of Delaware

Application May 1, 1936, Serial No. 62,402

Term of patent 7 years

To all whom it may concern:

Be it known that I, Archie Towart, Jr., a citizen of the United States, residing in West Caldwell, Essex County, in the State of New Jersey, have invented a new, original, and ornamental Design for a Siphon Bottle, of which the following is a specification, reference being had to the accompanying drawing forming a part thereof.

Figure 1 is an elevational view of a siphon bottle embodying my new design, the vertically disposed decoration being repeated at regular intervals around the circumference of the casing.

I claim:

The ornamental design for a siphon bottle as shown and described.

This specification signed this 29th day of April, A. D. 1936.
